UNITED STATES PATENT OFFICE.

BENJAMIN A. HUGHES, OF COLORADO SPRINGS, COLORADO.

ORE-CONCENTRATING TABLE.

1,343,266.

Specification of Letters Patent. Patented June 15, 1920.

Application filed March 17, 1917, Serial No. 155,539. Renewed March 22, 1920. Serial No. 367,828.

To all whom it may concern:

Be it known that I, BENJAMIN A. HUGHES, a citizen of the United States, residing at Colorado Springs, in the county of El Paso and State of Colorado, have invented certain new and useful Improvements in Ore-Concentrating Tables, of which the following is a specification, reference being had to the accompanying drawings.

10 This invention relates to ore concentrating tables of the reciprocating type, and particularly to the manner of riffling these tables.

15 The general object of this invention is to secure a better concentration of the ore than is possible with tables as ordinarily rifled and in this connection to provide for a scientific ore dressing and the separation of one mineral from another and to provide for as 20 large a head tonnage as is required to properly load the separating zones into which the table is divided.

25 A further object of the invention is to provide in connection with a table of this character a feed stratifying zone in which the material is first stratified in vertically disposed strata in the order of the specific gravities of the components of the material and to further so riffle the table that the mineral discharged from the feed stratifying zone will be eventually discharged upon a final or mineral stratifying zone in strata disposed across the table in correspondence with the specific gravities of the minerals.

30 35 A further object of the invention is to provide an initial rifled zone so constructed that it will uniformly distribute the material and feed water and counteract any underwashing tendency whereby fine mineral would 40 be carried over into the tailings before such fine mineral could sink under the coarse mineral and be protected in its travel to the final stratifying zone.

45 A further object in this connection is to provide a third, relatively long zone in which the riffles are disposed in a direction at an angle to the direction of inclination of the table and the direction of reciprocation of the table, these angularly disposed riffles 50 acting to check the speed of the mineral and bank it up against the upper sides of the angularly disposed riffles in this zone to thereby compact the ore bed and permit the fine material to sink under the coarser material.

55 Another object is to provide a fourth zone into which the angularly rifled zone dis-

charges, this fourth zone having riffles so disposed that the mineral will move forward more rapidly than in the angularly disposed zone and permit the freer longitudinal movement of the mineral and in this connection to provide a further rifled zone into which the last named zone discharges having riffles so disposed as to again check the speed of the mineral, these riffles being so placed 60 and directed as to provide for a final separation of the minerals and to secure a final pressure on the material which will force out the lighter particles therefrom so that these lighter particles will be carried downward 70 across the table to lower riffles and will be discharged upon the final stratifying zone at the proper point.

Other objects of the invention will be more specifically stated after the specific arrangement of the riffles on the table have been described.

My invention is illustrated in the accompanying drawings, in which:—

Figure 1 is a plan view of a concentrating 80 table having riffles disposed thereon, in accordance with my invention;

Fig. 2 is a longitudinal section of the concentrating table on the line 2—2 of Fig. 1;

Fig. 3 is a fragmentary transverse section 85 of the table to show the transverse increase in the height of the riffles from the upper side edge of the table toward the opposite side edge; and

Fig. 4 is a diagrammatic plan view to 90 show the general proportions of the table and the proportions of the several zones.

Referring to the drawings, and particularly to Fig. 1, 10 designates a concentrating table of the usual or ordinary form, this table being mounted for longitudinal reciprocation in any suitable manner, which reciprocation is given to the table by any suitable mechanism as, for instance, the mechanism 11 which is an ordinary form of mechanism for this purpose and requires no special description, this mechanism imparting to the table a reciprocation which causes the material on the table to have a tendency to move from the head or feed end of the table 105 to the foot or discharge end thereof. The table is supported in an inclined position as illustrated in Fig. 3, so that one edge, as for instance the edge α , is higher than the edge β . An end board 12 is disposed at the head 110 end of the table for retaining the material on the table. At the upper or feed side of the

table, at the receiving end, is disposed the feed box 13 of any suitable construction adapted to receive the material to be concentrated, together with feed water, and to distribute it over the receiving end of the table at the upper side thereof. A water box 14 extends the full length of the table along its upper edge α by which washing water is discharged upon the face of the table. The surface of the table 10 is a plane surface and the table is preferably of wood covered with linoleum to which the riffles 15 are secured in any suitable manner. These riffles 15 have a uniform width but taper from the head end of the table to the discharge end thereof, as will be later stated and these riffles gradually increase in height from the upper edge of the table to the lower edge thereof as will be later stated.

So far as described, the concentrating table is of common and ordinary form and my invention consists in providing an initial stratifying zone A, a final classifying or separating zone F, and providing a plurality of riffle zones B, C, D and E, between the initial stratifying zone and the final stratifying or classifying zone. The stratifying zone A is relatively large and extends approximately somewhat more than three-fourths of the length of the upper edge of the table and approximately one-third of the width of the table at its head end.

The riffle zone B is disposed below the stratifying zone A and has its riffles disposed in parallel relation to each other, to the upper and lower edges of the table, and to the direction of reciprocation of the table. Also disposed below the forward portion of the zone A and forward of the zone B is the zone C in which the riffles are disposed at an angle to the zone B, the riffles extending upward and forward, the upper riffles on this zone extending forward and transversely across the zone A. Forward of the zone C there is a zone D having parallel riffles, which riffles, however, are disposed at an angle to the riffles in the zone C and at an angle to the longitudinal axis of the table but at a less angle than the riffles in zone C. This zone D at its upper end is disposed beneath the forward narrow portion of the zone A, and forward of the zone D is a zone E having riffles which extend upward and forward at a greater angle than the riffles D to the longitudinal axis of the table. In other words, the riffles on zone E are disposed at an angle about the same as the riffles in zone C.

The line of demarcation between the riffles in zone B and those in zone C is indicated in the drawing by the dotted line $h-i$, and this line is approximately parallel with the head board 12. The line of demarcation between the riffles of zone C and those of zone D is indicated by the dotted line

$a-b$, this line starting about midway of the length of the table along its upper edge and extending down to the lower corner of the table at the discharge end. The riffles in zone E are about five inches in length in ordinary practice and terminate on the line $c-d$ extending from a point adjacent the water box 14 to a point on the discharge end of the table 10 about one-fourth of the width of the table from the lower corner. The riffles in zone E between the point d and the point b of the lower corner of the table discharge at the extreme end of the table, but the riffles in zone E above the point d discharge onto the final stratifying or classifying zone F. Below the lowermost and foremost riffle 16 of the zones C and D is a "middlings" zone G in which the riffles run parallel to the direction of reciprocation of the table and intersect with the lowermost riffles of the zone E. Along the lower edge of the table extend parallel riffles 17. These long riffles 17 are arranged to catch any mineral which may be washed out of its proper zone and cause the same to progress toward the discharge end of the table where it may be recovered for re-concentration. It is to be noted that the ends of the riffles in the zone C which confront the long riffles 17 are spaced from the uppermost of these long riffles by a space which may be $\frac{3}{8}$ " wide in practice.

All of the riffles are $\frac{5}{16}$ " wide and may have a uniform width for their entire length. The riffles taper longitudinally in height from the head end to the discharge end of the table and the thin or feathered edge of all of the riffles 15 is $\frac{1}{2}$ " thick on the lines $c-d, b$. The uppermost riffle at the head end of the table is $\frac{7}{16}$ " high and tapers uniformly to the discharge end of the table where it is, as before stated, $\frac{1}{2}$ " high. The riffles increase progressively in height from the uppermost riffles of the series to the lowermost riffles of the series, along the line $h-i$; these lowermost riffles at their head ends being $\frac{1}{2}$ " high. On the line $a-b$, the height of the riffles progressively decreases from $\frac{1}{2}$ " at b to $\frac{1}{2}$ " at a . Thus on the line $h-i$ the riffles increase in height downward across the table, while on the line $a-b$, the riffles decrease in height downward across the table. On the line between the zones D and E the riffles have an equal height and the extremities of the riffles of the zone E are equal in height. Of course it is to be understood that these figures are purely illustrative as the relative heights and spacing of the riffles may be varied depending on the character of the ore to be treated and the tonnage required. The number of riffles may also be varied. In actual practice, I use from 48 to 52 riffles depending upon the angle of the riffles in the zone C and in ordinary practice I space the riffles

flies 1" apart. Should, however, the spacing be more than 1" a less number of riffles will be used. Thus, for instance, the standard riffle which I have heretofore referred to is 5 $\frac{1}{2}$ " high at the head end and tapers to $\frac{1}{2}$ " high at the discharge end. This riffle is suited to an ore containing 20 to 40% mineral, but in treating a 5% ore a riffle depth of $\frac{3}{16}$ " at the head end and $\frac{1}{2}$ " at the tail end, 10 with a spacing of two inches between the riffles, will give better results than will the standard method of riffling. Furthermore, while I have illustrated the riffles of zone C as being disposed at a certain definite 15 angle to the riffles of zone B and the riffles of zones D and E as being disposed at certain angles, I wish it understood that these angles will be varied depending upon the character of the ore, as will be more fully 20 brought out later.

No means for separating and stratifying ore equals a smooth agitated surface upon which the ore is disposed. It is for this 25 reason that I have provided an initial stratifying zone A having a relatively large area. On this stratifying zone, the mineral is stratified according to its specific gravity before it enters onto either the riffle zone B or the riffle zone C. In this zone A several actions take place. The heavy bottom stratum of ore which receives the impulse of the longitudinal thrust caused by the reciprocations of the table is caused to 30 progress forward and into zone C, which, as before remarked, intersects the zone A or forms an inclined boundary for one end of that zone. The lighter strata or ore, however, move transversely of the table with a less longitudinal component. The 35 light gangue from the zone A passes into zone B and the longitudinally extending parallel riffles of zone B distribute the material and the feed water uniformly over that zone and thereby prevent any undue 40 washing tendency that would tend to carry the fine mineral over into the tailings before such fine mineral could sink under the coarser mineral and be protected on its travel to the mineral stratifying zone F.

45 It will be understood that the stratifying zone A is for the purpose of permitting all mineral to sink and engage the smooth surface and to become stratified in the order of its specific gravities, the heavier mineral moving forward and finding lodgment 50 against the uppermost riffle of zone C. Meanwhile the lighter gangue and mineral have been carried over into zone B, evenly distributed in this zone, and when the mineral reaches the first angular riffle in zone C, the separation of one mineral from another commences and at the same time the separation of all minerals from the gangue commences. The longitudinal movement of 55 the table forces the mineral particles for-

ward against the angular riffles in zone C with considerable force and inasmuch as these angular riffles impede the forward progress of the mineral particles, these angular riffles cause each mineral bed to 70 pack against the riffle just below, which has the effect of forcing out all particles of lighter specific gravity than the mineral 75 properly accompanying or corresponding to the space above such riffle and this prevents the wash water coming from the wash box 14 from passing through the mineral bed 80 with a detrimental effect which it would do were the riffles in zone C disposed parallel to the longitudinal axis of the concentrating table.

The angularity of the riffles in zone C, which angularity may be anything from $\frac{1}{2}$ " per foot to 5 inches per foot, depending on the character of ore treated, is for the 85 purpose of checking the speed of the mineral and causing it to bank against the upper side of the riffle, thus permitting the finer mineral to sink under the coarser mineral and force out all silicious particles. 90

The angularity of the riffles in zone D may also be varied to meet the different 95 conditions depending upon the ores being treated. The object of having the riffles in zone D at a less angle than the riffles in zone C is that this permits the mineral mass to move more rapidly and allows the riffles in zone C to feed onto zone D more readily.

Zone E has riffles in it of greater angularity than the riffles in zone D, the riffles 100 in zone E checking the speed of forward movement of the mineral and causes a final washing and discharge onto the mineral stratifying zone F.

I have stated before that the mineral particles are forced against the riffles in zone C with considerable force and are packed by the riffles thus forcing out all particles of lighter specific gravity than belongs in the particular space between two riffles. 105 Another effect also takes place in zone C and also in zone E, this effect being based upon the action of a natural law which may be termed the law of selection. If dry granular material is placed upon a plane 110 agitated surface, the particles of material will range themselves as follows:—The coarser particles will rise to the top and the finer particles will sink to the bottom, without respect to the relative specific gravities 115 of the particles. This, as above noted, is true for dry granular material. Where the granular material is wetted it is brought under the action of specific gravity, which law of relative specific gravity prevents the 120 lighter particles from sinking to the deck surface of the table, but does not prevent those fine particles which have the same specific gravity as the coarser particles from sinking downward through the mineral bed 125 130

to the deck surface of the table and being thereby protected from the heavy flow of wash water throughout zone C and to a less degree in zones D and E. This action 5 is not active to any appreciable extent, in concentrators having deep longitudinally extending riffles, that is riffles which are parallel to the direction of movement of the table, for the reason that the bed of mineral 10 is too light and buoyant and the mineral is not sufficiently packed. The wash water penetrates the mineral beds between the longitudinally extending riffles and washes out the "fines" and there is a resultant loss 15 of fine mineral.

For example, in an ordinary 16 foot table 20 concentrating an ore ground to say a 20 mesh screen and having longitudinally extending riffles on its surfaces, the time required for the ore to be passed from end to end of the table is about one minute and five seconds. Assuming that the riffles in 25 zone C are disposed at an angle of 15° to the direction of movement of the table, then these angular riffles in zone C reduce the speed of the mineral one-sixth and further 30 act to compress the bed of mineral one-sixth above its normal state where the ore is moving between longitudinally extending riffles. 35 and this compression in zones C, D and E will be in direct proportion to the angles in the riffles in these zones. It will be seen, therefore, that the action of the riffles in zone C and to a less degree in zones D and 40 E is to cause a compression of the bed of mineral to such an extent that a wash water will not penetrate the mineral bed and wash out the fines and, furthermore, that this packing and compression of the mineral bed 45 in zones C, D and E forces out all particles of lighter specific gravity than the mineral properly occupying any particular space between two riffles.

The angle of the riffles in zone E is for the 50 purpose of effecting final mineral separation, but I do not wish to be limited to the use of this zone E as the use of this zone is necessary only where ores are being concentrated having a heavy gangue, which so 55 closely approaches in specific gravity, the specific gravity of the mineral, that a last final pressure is necessary to force out the lighter particles whether they are gangue or mineral, so that these lighter particles may flow downward across the table, find their proper bed, and may enter the final classifying or stratifying zone F at a lower point and each at its proper place.

In the classifying zone F, the minerals are 60 arranged in longitudinally extending lines or stratas lying side by side in the order of their specific gravities, the heaviest mineral being of course at the upper portion of the zone F and the lightest mineral at the bottom 65 of the zone. It will be seen that

whereas in zone A the strata of mineral are superimposed in the order of their relative specific gravities, in zone F the strata are not superimposed, but are disposed or arranged in what may be termed a horizontal 70 relation instead of a vertical relation. The riffles which retain the relatively heavy particles of gangue it will be seen discharge at the end of the table and not upon the classifying zone F except, of course, those relatively long riffles 75 previously referred to which discharge at the end of the table.

The zone G is a middling zone and operates in conjunction with the long riffles at the bottom of the deck. Material gets into 80 this zone G by flowing over the last riffle of zone C. The end angles act to pass the lighter particles over the top of the riffles to the next lower and tend to place all particles in their relative order of specific gravity so 85 that the gangue may be more easily cut out.

It is also necessary to take into consideration the spacing of the riffles to afford sufficient riffle surface for the mineral and at the same time reduce the effort of the 90 riffles to force the gangue into the mineral zone. When the riffles have an excess capacity over the mineral contained in the ore they act to force the gangue into the mineral zone and it, therefore, follows that 95 the best concentrating effect is to be had by properly combining the factors of uniform riffle spacing and riffle depth with a proper angularity of riffles in the several zones and by providing a sufficiently large smooth 100 initial stratifying zone ahead of the riffles and by providing a large mineral classifying zone onto which the riffles discharge, the riffles entering this final classifying zone in a direction sufficiently transverse to the longitudinal thrust of the table as to deliver the various mineral strata from the table without unduly mixing one strata or group with the other strata or group next lower in the 105 zone and next lighter in specific gravity. 110

I have found by experiment that there is no definite angle at which the riffles in zones C, D and E must be placed for the reason that no two ores are exactly similar in constitution. Some ores can be crushed into 115 coarser particles than others and can be dressed in that state, whereas other ores require finer crushing to free the mineral from the gangue and still other ores require a much finer crushing not only to free the 120 mineral from the gangue but to free one mineral from the other. Each ore to be treated, therefore, is a problem peculiar to itself. The angularity of the riffles C, D and E must therefore be adjusted to the 125 various ores as accurately as practical knowledge and experience render possible.

For instance, a coarsely crushed ore, the mineral of which may have the size of 10 mesh, will not pack as firmly against a 130

riffle having an angle of 10° as fine mineral whose particles have passed through a mesh of 60 or 80. Therefore, a riffle whose angle has been designed for fine material will not be disposed at the proper angle for coarse mineral. It is, therefore, necessary to vary the riffle angles of zone C from 14 inches per foot to 4 inches per foot or even more and there will be a variation of riffle angle in zones D and E as requirements may indicate. Some mineral and gangue are so near alike in their specific gravities that a relatively great angle in zone C will be necessary in order to bank the mineral, check its advance along the riffles and force the gangue to rise to the top and pass over to the next riffle below. Conversely if there is a wide difference in the specific gravities of the mineral and the gangue, then the riffles in zone C may be disposed at a less angle which will be sufficient to cause the gangue and the mineral to be washed apart and sufficient to clean the mineral. In this case, of course, the gangue and mineral will travel faster toward the discharge end of the table and will be less compacted than where the riffles in zone C are disposed at a relatively great angle. The same rule applies to the riffles in zone E. Some mineral will be so thoroughly cleaned when it enters the zone E that only a very low angle of the riffles in zone E will be required while another mineral may require a very high angle owing to the presence of a very heavy gangue. Under all circumstances, however, the riffles are so designed in accordance with my invention as to cause the banking or compacting of the mineral by checking its travel and, furthermore, by causing the wash water to wash the gangue back toward the head of the table which makes the gangue line run well down toward the discharge side of zone C.

While I, of course, do not wish to be limited to any specific dimensions, I have illustrated a concentrating table having about the following proportions. The table shown in Fig. 1 is supposed to be 15 feet, 8 inches over all, the upper end of the line *a*—*b* is supposed to be about 8 feet from the discharge end of the table, while the upper end of the line *c*—*d* is supposed to be 4 feet, 9 inches from the end of the table. The table is 5 feet, 6 inches wide at its discharge end and the length of the zone B from the head of the table to the line *h*—*i* is about 2 feet, 5 inches. With this proportion of parts, the distance between *h* and *a* would be $5\frac{1}{2}$ feet, while the distance from *i* to the line *a*—*b* along the riffle in zone C extending from the point *i* would be 8 feet. I merely give these dimensions in order that the proportions of the feed stratifying zone, the mineral stratifying zone and the several zones B, C, D and E may be understood.

65 I am aware that it has been proposed to

provide a zone intermediate the head and discharge ends of the table and extending diagonally of the table in which the riffles shall be disposed at an upward and forward inclination to the line of reciprocation of the 70 table. I am not aware that it has been proposed to provide a relatively large stratifying zone for the purpose of disposing the different component parts of the material in vertical strata corresponding to the relative specific gravities of the components, and before the material passes on to the longitudinal riffles of zone B.

In some forms of concentrator, inclined riffles are provided but these riffles are relatively wide apart, that is, the riffles in the inclined zone are wider apart than the longitudinal riffles. This is not advantageous for the reason that the wider the space between the riffles, the greater is the cascade 80 of water over the riffle above the space. Now the material on the table or deck seeks to have a level surface and in a relatively wide space the material above the riffle may not extend above the base of the riffle next above 90 in which case the wash water will pour over the riffle next above with a heavy washing effect. This is the case also where the riffles are longitudinal and not disposed at an angle to the line of reciprocation of the table. Now 95 if a short diagonal zone is interposed between the longitudinal riffles, with relatively deep riffles and wide spacing, this tendency of the wash water to cascade over the riffles is reduced and there is an increased tendency 100 of the wash water to flow down the channel and to produce a strong washing effect rearward. This washing action, however, being parallel to the diagonal zone, destroys to a large measure any banking effect that may 105 be produced and where the diagonal zone is very short, the cleaning effect is produced by the strong back wash. Were the spacings of the diagonal riffles and the height of said diagonal riffles such that the material would 110 fill the space between the riffles when operating at an ordinary table inclination, there would be a reduction of this tendency to distribute the mineral bed and the washing effect would be confined to the surface of the 115 material. In that case there would be a banking effect just in proportion to the length of the diagonal zone and under these conditions, were the spaces between the riffles filled with a relatively solid compacted mass 120 of mineral, there is little or no back washing effect as the riffles are submerged in the bed of material and the washing tendency is transversely across the deck and is not influenced by the diagonal riffles.

125 In my system of riffling the riffles are uniformly spaced from each other, whereas if the riffle channels are wider in the zone C than in the other zones, the packing or compacting action of the inclined riffles will 130

be reduced and the "fines" will be liable to be washed out.

In actual practice I have proven that there is no back washing effect in my system of riffling, by pouring a small amount of black oil on the water at the upper side of the zone C and I find that as the oil travels toward the lower side, the oil makes a small advance toward the discharge end of the table as far as the riffles are filled, but below that point, where there is not enough material to fill the riffles, a rearward wash is plainly apparent. Thus the banking and compacting effect on the mineral bed is due to the angularity of the riffles and the longitudinal thrust of the table. The action of the table thrust upon the mineral bed is what forces out the lighter particles and passes them over the riffle to the next riffle below and a number of tests show clearly that in my system there is no apparent back wash on the mineral bed.

Again in my system of riffling less than 30% of the rifled surface has longitudinally extending riffles, while 70% has inclined riffles. Thus during 70% of the travel of the ore over the riffles, the ore beds are being compressed and the lighter particles of gangue, etc., are being squeezed out and carried away.

Again it will be noted that in my system, the uppermost riffle in zone C is relatively one-third shorter than that riffle of zone C which extends from the lowermost riffle of zone B and that the lengths of the riffles in zone C increase progressively downward across the table. Thus in the upper mineral beds composed of very heavy minerals, the compressive action is of relatively shorter duration than in the lower beds where the light minerals collect and where the gangue approaches most nearly the weight of the minerals collected in these lower beds and where, therefore, a longer action must be provided for in order to secure this more delicate separation.

The line *c-d* defining the discharge ends of the riffles is disposed at an angle across the zone F in order to cause the wash water to wash backward and downward.

It will be understood that the zone D is absolutely essential to the proper working of zone C. Zone D is set at a low angle in order to move the bed rapidly from the zone C owing to the riffles having less depth than the riffles in zone C. This allows zone C to discharge its load freely. Zone E is very essential where ores are treated having a heavy gangue. Only with ores of an extremely light gangue and a very heavy mineral do I contemplate using a relatively low angle in zone E. On all ores of heavy gangue I will use a high angle. The zone B is relatively of less importance than any zone of

my system, yet it is highly essential to a proper operation of the remainder of the system. Zone C is the absolutely vital zone but each of the zones has an important specific function.

The banking and cleaning effect in my system is due to the long angular zone C in conjunction with the angular riffles, the wash water flowing over the top of the riffles and over the beds of ore and acting directly on the top of the particles, there being no chance for the water to cascade over the top of the space, because the space or channels between the riffles are full to the top of the riffles and, therefore, all wash is transverse. The angle of deck inclination may, of course, be changed depending upon the ore being treated, for instance, on lead carbonates, I use an angle of about $\frac{1}{2}''$ to $\frac{3}{4}''$ per foot.

It will be seen that in its complete form my system of riffling includes the use of six riffle zones A, B, C, D, E, F. Each zone has its separate and distinct function to perform, and at the same time, is dependent upon the correct action of all the zones acting conjointly, thereby forming a system of riffling, in which no single zone is capable of producing results that equal the results obtained by the use of all zones working in harmony.

The initial zone A is the zone which receives the feed, and is formed by the top riffle. In this zone are placed, one or more short riffles, spaced 8 to 10 inches apart, so arranged as to form mineral beds. These riffles have less length than the feed box with a depth nominally the same as the top riffle.

The object of these riffles is to form beds of stratified mineral and also to hold the mineral at the top of the riffle system and prevent it passing with the pulp down to the middle of the table, as would occur very largely were these riffles not used. The riffle which forms this zone does not have holding capacity to prevent a large amount of the mineral from entering zone B.

The object of zone A is to trap out and stratify the mineral into vertical strata, which is progressed forward and the lighter strata shaved off to a lower position, without disturbing or breaking up the various strata as they pass through the various zones following.

Zone B is a short longitudinal zone, and is so arranged for the purpose of forming a light buoyant bed of material, in which the mineral can settle quickly and be progressed into the following angular zone C, and before the mineral can pass far down in zone B. At this point two objects are sought: 1st to stratify and, 2nd to retain all mineral as high up in the riffle system as possible, which in the final effort, prevents a heavy mineral from having to cross under the line of lighter

mineral, in order to occupy its proper place in the final finished zone F, as is the case with the old system of riffling.

The mineral beds in zone B also permit the fine mineral to sink and pass under the coarse mineral, and owing to the compact form of the mineral beds, these fines are protected from the cross wash and follow this bed to the point of delivery. This action is due to the natural law of "selection."

Zone C is arranged angular, for the purpose of forming a compact slow moving mineral bed, which receives the stratified mineral from zones A and B and progresses the same in a compact form, constantly squeezing out all the lighter particles, and constantly concentrates the mineral as it advances, and as the riffle depth grows less, the top strata are sheared over to a lower position in the transverse angle of the table; this action continues throughout the length of this zone.

The concentration made in zones A—B—C, are only part of the final effort of all zones. All material from zone C passes to zone D which has less angularity than zone C. The object of this is to progress the material at a more rapid rate, and to produce more buoyancy to the mineral bed, while the top strata are being sheared over to a lower position, before entering the final riffle zone E, which has its greater angularity than any of the preceding zones.

The object of this, is to form a compact mineral mass such that no light particles can remain in the stratum not composed of particles of similar specific gravity. In other words, particles of dissimilar gravities cannot occupy the same stratum in zone E.

All the mineral is completely concentrated and accurately stratified in the combination of riffle zones, and delivered into zone F, in clean lateral strata and quickly discharged from the table, before it is possible for one stratum to climb another stratum due to the smooth surface and transverse angle of the table, together with the washing effect of the dressing water, as, under these conditions, the tendency of the clean mineral is, for the heavy stratum to pass under the next lighter stratum, and therefore the overlap between each mineral stratum is proportionate to the length of the smooth zone, and the time required for the mineral to pass off the smooth zone.

Zones E and C are both flexible zones, that is, their angularity is governed by the character of the material which they are required to treat; both as regards the nature of the ore, as well as the texture, or mesh to which the table feed is crushed. In other words, the riffle system is adjusted to the requirements of the ore, and not an arbitrary system, like the old riffle system, wherein an attempt is

made to make the ore fit the riffle system, which is the direct cause of so many failures to the many different classes of ores.

The angularity of zone E depends especially upon the relative gravities of the various particles of both the mineral and gangue, while the angularity of zone C is governed by the texture or mesh of the table feed, in fact this system is arranged to meet the special requirements of the ore in every case.

It will be understood that the deck plane of my concentrating table is all in one plane with the entire surface from the water box to the lower edge of the table lying at the same lateral inclination. It will also be seen that the zone A is approximately triangular in form, being large at the head end and relatively wide, and very narrow where it joins zone F so that the zone F would be entirely cut off from zone A at the point were it not for the water box and in order to have the riffle tips disposed for cleaning (in case of oxidized minerals cementing to the deck when the table is stopped, which is a common difficulty). This difficulty makes it desirable to keep the riffle tips all in the clear. Therefore, the riffle tip of the uppermost riffle does not touch the water box but at this point only clean, heavy mineral passes, which never has a depth in excess of one inch above the riffle tip and, therefore, only the film of wash water passes over the smooth surface above, so that in fact zone A is a separate and closed zone and is not joined in action to zone F, in other words only the heaviest mineral which has been thoroughly cleaned passes into the zone F directly from the zone A.

The action of the material in zone A is as follows: The feed water and pulp pass across this zone toward the riffle zones B and C, with about three-fourths of the feed of the pulp passing toward zone B. Immediately upon this smooth surface of the zone A, all the particles are segregated and pass laterally down the inclined face of the zone A rapidly until the uppermost boundary riffle is reached. Here, the material is banked and formed into a bed some six or seven inches wide, and it is in this bed that the real stratification takes place. This bed follows the upper riffle or boundary riffle with a varying width to about one inch at the point c. Beyond the end of the feed box 13 there is no material in zone A except that portion banked against the boundary riffle, and as the table motion is smooth and the mineral bed is advanced without disturbing the strata of this bed and as the riffle depth is less as the bed advances, the top strata of this riffle bed are sheared over the boundary riffle into zones C and D, it being noted that the inclined riffles of zones C and A inter-

- sect and cut across the end of zone A so that this zone has a long, inclined, upwardly extending boundary so that nearly all the material in zone A must, of necessity, pass into zones C and D.
- The zone A stratifies the mineral, as before explained, the riffled zones classify the mineral, and the final zone F receives the separated and classified mineral from zone E and delivers the same from the table, each class of mineral being separated from the other class or spread out so that the operator may see better how to separate the classes of mineral into separate launders. The angular boundary of zone A and the angular riffles in the riffle zones C and D and E produce separating results through the action of compressing the mineral beds, squeezing out the lighter particles, and causing these lighter particles to shear over the riffles as the mass is progressed forward along riffles which decrease in height and which are placed on an inclined surface. The only zone which does not form a compressed bed is the zone B, where the riffles extend parallel to the direction of motion of the table. This zone B forms a light and buoyant bed of material and only acts to sink all mineral quickly so that it may be later acted upon by the squeezing and compression action in zone C. It is also to be understood that my table is to be reciprocated by that form of mechanism known as the "toggle motion," which is quite commonly used in concentrating tables, which produces the same progressive movement as the bed of material moves forward and does not set up a remixing action as is produced by mechanism such as that used to produce a "bumping motion." This commonly used toggle motion produces the forward movement of the material on the table by moving the table forward at such a rate that all the particles follow the surface. This stroke starts slowly and stops slowly without impact or disturbance of the mineral bed, and has its greatest velocity near mid-stroke. The return stroke is similar, except that its rate of speed is faster and the deck surface, therefore, is slipped under the material without disturbance or stirring effect. This stroke is usually about $\frac{3}{4}$ " long and rarely over 1" long, so that this action can easily take place within the space between the angular riffles, which are spaced about 1" apart and without any disturbance of the strata which may be formed from agitation by this motion. In the angular zone C where the mineral beds are formed by compression, the angularly disposed riffles permit the fine mineral to sink and pass under the coarser minerals and in wet table concentration specific gravity acts to select the particles of like gravity so that only the heavy particles can enter a stratum of like gravity composed of coarser particles. This

means that fine lead will enter the coarse lead stratum, fine iron will enter the iron stratum, and the fine zinc will enter the zinc stratum, and that the fine gangue particles of the heaviest class will enter the heavy gangue stratum on top of the zinc stratum. Vertical stratification will place the minerals in the order named in such arrangement or stratification, and thus if the mass is compressed into a compact, heavy bed, such as is produced by the inclined riffles C and D and E, the fines are protected from the coarse wash. If, however, the bed is light and buoyant, such as is produced by longitudinal riffles, as the riffles B, then the fines will be washed out and a large part lost with the slimes water.

Having described my invention, what I claim is:—

1. A longitudinally horizontal but transversely inclined, longitudinally reciprocating, concentrating table having no lateral component in its movement and having its upper surface disposed entirely in one plane, said table having a relatively large, smooth, initial stratifying zone at the head end of the table, the lower boundary of this stratifying zone extending upward and forward at an inclination to the direction of movement of the table, a relatively large, smooth, flat, classifying zone at the discharge end of the table and extending transversely thereof from the upper side toward the lower side of the table, and a zone disposed between the stratifying zone and classifying zones and separating them from each other having riffles inclined upward and toward the discharge end of the table and at such an angle to the line of motion of the table as to offer material resistance to the progress of the material, the channels defined by said inclined zone of riffles all discharging upon the final classifying zone, and the uppermost riffle forming an upwardly inclined boundary to the lower edge of the stratifying zone against which mineral in the stratifying zone will bank.

2. A longitudinally horizontal but transversely inclined concentrating table having longitudinally reciprocating movement without lateral component and having its upper surface disposed in one plane, said table having a relatively large, smooth, initial stratifying zone at the head end of the table, relatively wide at its head end but growing narrower toward the discharge end, a relatively large, smooth, flat, classifying zone at the discharge end of the table and extending transversely thereof, and a zone disposed between the stratifying and classifying zones and separating the one from the other and having riffles inclined upward and toward the discharge end of the table and extending transversely to the stratifying zone, the uppermost riffle forming

ing the uppermost boundary of said riffled zone extending upward and forward at an inclination to the line of motion of the table and forming the lower boundary of 5 the stratifying zone, the channels defined by said inclined riffles all discharging upon the forward classifying zone, the ends of said riffles being disposed in a line extending downward and forward toward the 10 discharge end of the table.

3. A transversely inclined concentrating table having longitudinal reciprocation without any lateral component, said table having a relatively large, smooth, initial 15 stratifying zone at the head end of the table, a relatively large, smooth, flat classifying zone at the discharge end, and a plurality of zones disposed between the stratifying and classifying zones having uniformly 20 spaced riffles inclined upward and toward the discharge end of the table and extending transversely to the stratifying zone, the riffles in the several intermediate zones having different relative angular 25 relations to each other, the channels defined by said inclined riffles discharging upon the final classifying zone, said inclined riffles being disposed at such an inclination to the line of motion of the table as to offer material 30 resistance to the progress of the material being concentrated.

4. A longitudinally horizontal but transversely inclined concentrating table having its upper face disposed in one plane and 35 having longitudinal reciprocation with no lateral component, said table having a relatively large, smooth, initial stratifying zone extending from the head end of the table along the upper margin thereof and being 40 relatively wide at the head end of the table and narrowing toward the discharge end thereof, the table also having a relatively large, smooth, flat, classifying zone at the discharge end of the table extending downward 45 from the upper margin thereof, and an intermediate zone extending downward from the stratifying zone to the lower edge of the table, and having riffles extending at an angle to the line of movement of the 50 table and all discharging upon the final classifying zone at an angle upward and toward the discharge end of the table, the riffles being uniformly spaced apart for their entire length, and the angle of the 55 riffles relative to the line of motion of the table being such as to offer material resistance to the progress of the material being concentrated whereby to cause compression of the mineral beds formed between 60 said riffles and squeeze out the lighter particles therefrom, said uppermost, inclined, riffle of said intermediate zone defining the lower, angular edge of the initial stratifying zone whereby said intermediate riffled 65 zone substantially separates the initial

stratifying zone from the final classifying zone.

5. A longitudinally horizontal transversely inclined concentrating table having a relatively large smooth initial stratifying zone 70 extending from the head end of the table longitudinally along the upper margin thereof and a final classifying zone at the discharge end of the table extending downward from the upper margin thereof toward the 75 lower margin thereof, the table at its head end below the stratifying zone being formed with a zone having parallel uniformly spaced riffles extending parallel to the line of movement of the table and forward of 80 this zone being formed with uniformly spaced riffles extending upward and toward the discharge end of the table and extending transversely at such an inclination to the line of movement of the table as to cause 85 the riffles to offer material resistance to the progress of the material and transversely to the initial stratifying zone, the upper corner of this inclined riffle zone approximately touching the upper margin of the 90 table whereby to separate the stratifying zone from the classifying zone, the discharge ends of the channels between the riffles discharging upon the classifying zone and being disposed on a line extending 95 downward and toward the discharge end of the table and extending transversely across the lower portion of the classifying zone, the lowermost inclined riffles extending 100 to the extremity of the table.

6. A longitudinally horizontal transversely inclined concentrating table having longitudinal reciprocation with no lateral component having at its head end a relatively large smooth initial stratifying zone, extending longitudinally along the upper margin of the table, the lower boundary of the stratifying zone extending upward and toward the discharge end of the table nearly to the upper margin of the table, an approximately triangular classifying zone relatively large in area disposed at the discharge end of the table and extending from the forward end of the stratifying zone to the discharge end of the table, the base of 110 the triangle being at the upper edge of the table and the apex of the triangle extending downward, the table being provided below the head end of the stratifying zone with a zone having uniformly spaced riffles extending parallel to the line of movement of the table and forward of this zone with a zone having uniformly spaced riffles extending upward and toward the discharge end of the table at such an inclination to the line 115 of motion of the table as to offer material resistance to the progress of the material being concentrated, said zone defining the lower forward boundary of the stratifying zone and said riffles terminating on a line 120 125 130

extending downward and toward the discharge end of the table and defining the lower boundary of the classifying zone, the lowermost riffles of the upwardly inclined 5 riffles extending to the extremity of the table.

7. A longitudinally horizontal transversely inclined concentrating table having longitudinal reciprocation but no lateral component having at its head end a relatively 10 large smooth initial stratifying zone extending longitudinally along the upper edge of the margin of the table, the lower boundary of the stratifying zone extending upward and toward the discharge end of the table nearly to the upper margin of the 15 table, an approximately triangular classifying zone relatively large in area disposed at the discharge end of the table and extending from the forward end of the stratifying zone to the discharge end of the table, the apex of the triangle being toward the lower edge of the table, the table being provided below the head end of the stratifying zone with a zone having longitudinally 20 extending riffles parallel to the sides of the table and forward of this zone with a zone having riffles extending upward and toward the discharge end of the table, said zone defining the lower forward boundary of the stratifying zone and said riffles terminating 25 on a line extending downward and toward the discharge end of the table and defining the lower boundary of the classifying zone, the lowermost of said upwardly inclined 30 riffles extending to the extremity of the table, the lower margin of the table being provided with a plurality of longitudinally extending riffles extending from the head 35 end to the discharge end of the table, the upwardly inclined riffles being uniformly spaced, and the inclination of the riffles to the line of motion being such as will materially resist the forward progress of the 40 material being concentrated.

8. A transversely inclined concentrating table having longitudinal reciprocation with no lateral component and having a feed box and a water box extending along its upper 45 margin, the table having a relatively large feed stratifying zone at its head end and extending toward the discharge end of the table and a relatively large classifying zone at the discharge end of the table and extending downward from the upper margin 50 thereof, the table below the rear end of the stratifying zone having a plurality of riffles extending parallel to each other and to the line of reciprocation of the table, the table forward of this last named zone being provided with riffles extending upward and toward the discharge end at an angle 55

tending transversely across it, a third riffle zone disposed in advance of the last named riffle zone and having riffles extending upward and toward the discharge end of the table but at a less angle than the riffles in 60 the second named riffle zone and a fourth riffle zone having riffles extending upward and toward the discharge end of the table at a greater angle than in the second named 65 riffle zone, the discharge ends of the channels defined by said last named riffles being disposed on a line toward the discharge end of the table at an angle to the line of reciprocation and from the upper margin of the table to the discharge end thereof and 70 intersecting said discharge end at a point above the lower edge of the table.

9. A transversely inclined concentrating table having longitudinal reciprocation with no lateral component and having a feed box 75 and a water box extending along its upper margin for its entire length, said table having a flat smooth relatively large feed stratifying zone extending along the upper margin of the table from the head end toward 80 the discharge end and having a flat smooth relatively large classifying zone at the discharge end and extending downward from the upper margin of the table nearly to the lower margin thereof, the table below the 85 head end of the stratifying zone having a zone formed with longitudinally extending riffles parallel to the line of motion of the table, said riffles at the lower edge of the table extending longitudinally the full 90 length of the table, the table in advance of the longitudinally riffled zone being formed with a second riffled zone having upwardly and forwardly inclined uniformly spaced 95 riffles extending at a predetermined inclination to the line of motion of the table and transversely of the stratifying zone, a third successively disposed riffled zone having riffles extending at a less inclination than in the second riffled zone and a fourth relatively short riffled zone having riffles disposed at a greater inclination than in the 100 zone immediately preceding the ends of the riffles in the fourth zone being disposed on a line bounding the lower edge of the classifying zone and extending downward and forward from the upper margin of the table to the forward edge thereof above the lower edge of the table, the line of juncture between the riffles of the second named riffled 105 zone and of the third named riffled zone extending downward and forward from the upper margin of the table to its lower forward corner at a greater angle than the angle of the line bounding the lower end of 110 the classifying zone.

10. A longitudinally horizontal trans-

disposed entirely in one plane having a relatively large, smooth, initial stratifying zone at the head end of the table, a relatively large, smooth, flat classifying zone 5 at the discharge end of the table, and a zone disposed between the stratifying and classifying zones and substantially separating said zones having riffles inclined upward relative to the line of motion of the table 10 and toward the discharge end of the table and extending transversely to the stratifying zone, the channels defined by said inclined riffles discharging upon the final classifying zone, the uppermost riffle of the riffles 15 fled zone forming the boundary of the lower margin of the stratifying zone, the riffles being uniformly spaced along their entire extent and uniformly tapering from the head end to the discharge end of the riffles, 20 but said riffles at the beginning of the inclined riffle zone progressively increasing in height from the upper margin of the table to its lower margin.

11. A laterally inclined concentrating table 25 having longitudinal reciprocation with no lateral component, the table being formed at its head end and adjacent its highest margin with a longitudinally extending stratifying zone and below this zone with a longitudinal riffled zone, the riffles for a portion of their length extending upward and toward the discharge end of the table at an angle to the line of motion of the table 30 and forming an upwardly inclined boundary 35 to the stratifying zone, the riffles forming

the boundary of this zone extending unbrokenly from the head end of the zone to the discharge end thereof, means for discharging pulp upon the stratifying zone at the head end thereof and causing the pulp 40 to flow transversely of the table, and means for discharging wash water upon the table along the upper margin thereof and in a direction transverse to the longitudinal axis 45 of the table.

12. A reciprocating laterally inclined concentrating table moving in a right line direction with no lateral component, having means for supplying wash water along the upper margin of the table, and initial stratifying zone, a final mineral classifying zone, and riffles extending longitudinally of the table and defining ore channels, said riffles being uniformly spaced but being so disposed for a portion of the length of the 50 table as to resist the forward movement of the ore along said channels to thereby compact the ore beds in the channels and squeeze out relatively light particles, the discharge ends of the channels being so formed as to 55 exert a final compressing action on the ore in said channels just previous to its discharge upon the final classifying zone.

In testimony whereof I hereunto affix my signature in the presence of two witnesses. 60 65
